[57] CLAIM

The ornamental design for a capo for a stringed musical instrument, as shown and described.

DESCRIPTION

FIG. 1 is a top perspective view of a capo for a stringed musical instrument showing my new design;

FIG. 2 is a top perspective view of the faces of the capo opposite those of FIG. 1;

FIG. 3 is a fragmentary perspective view of another embodiment of the latch shown in FIG. 2; and

FIG. 4 is a fragmentary perspective view of another embodiment of the guide shown in FIG. 2.

FIG. 1

FIG. 2

FIG. 3

FIG. 4
